UNITED STATES PATENT OFFICE.

JOHN W. KITTREDGE, OF AKRON, OHIO.

TOOTH CONSTRUCTION FOR DIGGING-BUCKETS.

1,333,852.

Specification of Letters Patent. Patented Mar. 16, 1920.

Application filed March 30, 1915. Serial No. 18,203.

To all whom it may concern:

Be it known that I, JOHN W. KITTREDGE, a citizen of the United States, residing at Akron, in the county of Summit 5 and State of Ohio, have invented a new and useful Tooth Construction for Digging-Buckets, of which the following is a full, clear, and exact description.

My invention relates to teeth for buckets 10 or dippers on drag line excavators, steam shovels, dredges, or wherever strong sharp teeth are necessary.

The objects of my improvements are:—

1st. To provide sharp teeth thereby enabling them to more quickly enter the ground without sliding over it; to more easily penetrate the ground after entering; and to enable a drag bucket to enter the ground at a less angle with the line of pull, 20 thereby economizing power and facilitating the digging operation.

2nd. To provide teeth of such simple form that they can be made of very hard steel with very little shaping or working; 25 to provide teeth so small that they can be made of a fine quality of steel without excessive cost; and to protect them and thereby enable them to withstand severe usage.

3rd. To provide a bucket bottom with 30 sockets of strong and simple form, requiring little accurate fitting and expensive workmanship.

4th. To provide teeth such that dull ones can be removed and sharp ones inserted in 35 the field, easily, quickly, and with few tools or appliances.

5th. To provide teeth that will not wear round or blunt under severe usage.

6th. To so space the teeth on the jaw or 40 lip of the bucket that they will cut wider than the body of the bucket and leave a clearance between the sides of the bucket and the hard, unbroken ground.

7th. To set the teeth at such an angle 45 with the bottom of the bucket, that the bucket resting on its bottom will tend to force the teeth into the ground.

I attain these objects by the design illustrated in the accompanying drawing in 50 which:—

Figure 1 is a side elevation of the teeth as applied to an ordinary drag line bucket; Fig. 2 is a front elevation of the teeth and bucket with the bail removed; Fig. 3 is an 55 enlarged section on the center line of Fig. 2, with elevations of the tooth and filler

bolt. Fig. 4 is a view in side elevation of one of the teeth employed. Fig. 5 is an end elevation of the tooth shown in Fig. 4, and Fig. 6 is a side elevation of an ejector 60 employed for removing the teeth. A given piece carries the same number throughout the several views.

The tooth 1 is set in the jaw 2 and held in place by any suitable means, as by the 65 taper pin 3. The jaw is preferably a steel casting. The tooth is adapted to be made from hard, high grade steel by simply grinding the points and making the notch. Of small size and simple workmanship, it 70 can be made at moderate cost. Grooved lengthwise, as shown, it tends to hold its point, not only from the quality of the steel, but also from its shape, the comparatively thin flanges wearing away faster 75 than the massive center. This also facilitates grinding. The tooth of high grade tool steel is much harder than the cast steel jaw. The relatively soft steel jaw wears away faster than the hard steel tooth. The 80 combined tooth and holder thus tend to retain a tapering or pointed form due to the difference in the hardness of the two metals. Dull teeth can be driven out and sharp ones inserted in the field with simply a hammer 85 and punch. The filler bolt 4 is simply to facilitate driving out the tooth, as otherwise the hole would be filled with mud and gravel. The outer teeth are the outermost points of the jaw and incline slightly 90 outward and are wide enough to leave a clearance between the body of the bucket and the hard unbroken ground. The teeth also incline slightly downward, when the bottom of the bucket is level, to set them 95 easily and quickly into the ground. Sharp teeth will enter the ground more nearly in the line of the pull than will large dull ones, filling the bucket better and greatly economizing power. 100

Having thus described my invention, I claim as new and desire to secure by Letters Patent:—

I claim,

1. A digging or scoop bucket provided 105 along its lower front working edge with a plurality of tooth receiving sockets the axes of which are forwardly and downwardly inclined, said bucket further provided with openings less in diameter than said sockets 110 and extending rearwardly therefrom, an ejector mounted in each socket with the

- head of said ejector of proper size to be 5
slidable in said recess and the stem there-
of extended in the opening connecting
therewith, and a tooth secured in each
socket.
2. A digging or scoop bucket provided
along its front working edge with a plu-
rality of tooth receiving sockets, an ejector
in each socket, a tooth in each socket, and
means for temporarily and snugly locking
each tooth in its socket.
3. A digging or scoop bucket provided
along its lower working edge with a plu-
rality of tooth receiving sockets, an ejector
mounted in each socket, said ejector com-
prising a head adapted to seat near the bot-
tom or rear wall of said socket and pro-
vided with an extended stem, a tooth
adapted to be mounted in each socket.
4. A digging or scoop bucket provided
along its lower front working edge with a
plurality of tooth receiving sockets, an
ejector comprising a head slidably mounted
in said socket and arranged to seat near
the rear wall thereof and furthermore pro-
vided with an extended stem, said socket
provided with a transverse opening ap-
- proximately tangential to the recess in the
socket, a tooth arranged to be seated in the
recess in said socket and means for locking 30
said tooth in said socket.
5. The combination with a digging or
scoop bucket provided along its lower front 35
working edge with a plurality of tooth re-
ceiving sockets, of a plurality of teeth hav-
ing a plurality of longitudinally-extending
grooves in the outer faces thereof mounted
in said sockets.
6. The combination with a digging or
scoop bucket provided along its lower front 40
working edge with a plurality of tooth re-
ceiving sockets, of a plurality of teeth each
having two pairs of longitudinally-extending
grooves in the outer face thereof with
the members of each pair of grooves dia- 45
metrically opposite to each other.

In testimony whereof, I have signed my
name to this specification in the presence of
two subscribing witnesses; this 27th day of
March 1915.

JOHN W. KITTREDGE.
